Attorney.

UNITED STATES PATENT OFFICE.

JOHN WILLIAM GOMERSALL, OF MANCHESTER, ENGLAND.

RUBBER-FORCING MACHINE.

1,422,561.

Specification of Letters Patent. Patented July 11, 1922.

Application filed November 1, 1920. Serial No. 421,153.

(GRANTED UNDER THE PROVISIONS OF THE ACT OF MARCH 3, 1921, 41 STAT. L., 1313.)

To all whom it may concern:

Be it known that I, JOHN WILLIAM GOMERSALL, subject of the King of Great Britain and Ireland, and resident of Manchester, in the county of Lancaster, England, have invented certain Improvements in Rubber-Forcing Machines (for which I have filed an application in Great Britain on May 30, 1918, which issued as Patent No. 150,754 on Sept. 16, 1920), of which the following is a specification.

This invention relates to improvements in rubber forcing machines and has particular reference to improved means for feeding the rubber material to the forcing screw or scroll.

Prior to the date of my invention the rubber material has been fed to the screw or scroll in two ways. In the first case the material is pressed by a stick into a small hopper or throat-opening, communicating with the scroll chamber, a fair amount of pressure requiring to be exerted to cause the rubber to become engaged and to be forced forward by the scroll. Hence strong girls or youths are required for the purpose. In the second case, later developments took the form of a pair of positively-driven adjustable feed rollers located on the machine framing above the throat opening and scroll. Such latter arrangement is an expensive construction and has the additional disadvantage that when it is desired to run the forcing machine for short periods on different colours of rubber material it is very difficult to clean out the throat and attendant parts after each colour before commencing with the next.

My invention is designed to provide a novel roller feeding arrangement and a removable doctor mechanism designed to avoid the defects referred to.

My invention will be fully described with reference to the accompanying drawing in which,

Fig. 1. is a sectional plan of so much of a rubber-forcing machine of known construction as is necessary to show the character of my invention and

Fig. 2. side elevation and

Fig. 3. sectional end elevation of same on line 1-2 of Fig. 1.

With the aforesaid end in view I re-arrange the throat *a* leading to the scroll cham-

ber *b* and constitute one side of it by a feed roller *c* fixed upon or formed integral with a shaft *d*. The latter is supported in bearing blocks *e* having fitting strips *f* engaging with grooves formed in the casing or frame *g* of the forcing machine, the sides *h* of the blocks fitting in open gaps *i* in said frame. The bearing blocks are held in position against the shaft by caps *j* secured and adjusted by studs and nuts *k*. The shaft has formed in one with it a driving wheel *m*, 65 adapted to gear with a wheel *n* formed in one with or secured to the usual scroll *o* to enable the roller *c* to be driven positively. The roller *c* acts in conjunction with the scroll *o* to form a feed mechanism. It is mounted 70 so that its periphery is a little distance away from the scroll, so leaving a passage *p* for the rubber material. The roller *c* is preferably driven at a peripheral speed a little in excess of that of the scroll *o* so as to exert 75 a pulling action upon the material and effectively feed it to the scroll. The face *q* of the throat opposite to the roller may be vertical or partly vertical or inclined as shown to form with the roller *c* a suitable 80 entrance opening or throat *a*. The roller *c* may be adapted to be adjusted horizontally to and from the scroll *o* to decrease or increase the space *p* between them, if required.

In conjunction with the roller *c* I employ 85 an adjustable and removable doctor *r* for cleaning the roller *c* of adherent rubber as it rotates. This doctor is located in a space *s* below and at the inner side of the roller *c*, its inner face *t* being tangential to the scroll. 90 It is carried on a support *u* extending to the outside of the machine frame *v*. This support terminates in a screw *w* fitted with a wing or other nut *x* and between the latter and a fixed abutment *y* is located a spring 2 95 which can be adjusted by the nut to always draw the doctor to the roller *c* apart from the pressure exerted by the rubber material being fed into the machine the screw *w* passing freely through the hole 3 in the abutment *y* which forms part of the plate afterwards referred to. Vertically the doctor is supported by a removable plate 4 carried at the bottom of the space *p*. The plate 4 is held in position on the frame *v* by screwed 100 studs 5 and nuts 6 and a guide pin 7. By removing plate 4 first the doctor *r* can be taken away from the roller *c* and ample

room be left for cleaning the space beneath the roller.

What I claim as my invention and desire to secure by Letters Patent is:—

- 5 1. In a rubber-forcing machine, the combination with the single roller of a doctor located below it and adapted to be automatically drawn towards the periphery of the roller by a spring, and a spring operatively connected with the said doctor.
- 10 2. In a rubber forcing machine, a feed

roller, a shaft supporting said roller having a driving wheel forming part of said shaft, bearing blocks for the shaft supported and guided in gapped openings of the machine frame and removable caps for the bearings.

In testimony whereof I have hereunto set my hand in the presence of two witnesses.

JOHN WILLIAM GOMERSALL.

Witnesses:

WILLIAM W. TAYLOR,
HENRY CRUSE.
